UNITED STATES PATENT OFFICE

2,491,707

FIREPLACE SCREEN

Robert E. Boyden, Los Angeles, Calif.

Application December 26, 1945, Serial No. 637,187

3 Claims. (Cl. 160—371)

1

This invention relates to screens and has particular reference to fireplace screens for preventing embers and the like from being thrown outward by a fire during the process of combustion.

Heretofore, fireplace screens in general have comprised screens of substantially evenly spaced cross mesh wire strands of relatively close spacing. The meshed wire, forming relatively small square or substantially square openings, tend to reduce the passage of heat outward from the fire by reflecting a large portion thereof back toward the fire. Such screens also form a visible barrier which cuts down visibility and thus detracts from the natural beauty and appearance of a fire and fireplace settings. This is due to the large total amount of projected area of the various strands and also, no doubt, to the phenomenon of diffraction of light through the relatively small openings formed by the wire strands.

It therefore becomes a principal object of my invention to obviate the above mentioned disadvantages of fireplace screens.

A further object is to render a fireplace screen substantially invisible at ordinary distances.

A further object is to reduce the tendency of a fireplace screen to accumulate soot and other products of combustion as well as dirt and dust.

A still further object is to facilitate cleaning of a fireplace screen.

I have discovered that embers, ashes, etc. thrown off by a fire are generally of equal size in all three dimensions or, if elongated or planar in form, are thrown off with their axes or planes extending heterogeneously in different directions, and upon this discovery I have found that a screen made of parallel wire strands extending in one direction only will bar substantially the same amount of embers and ashes from passing therethrough as a series of cross meshed strands of the same spacing. At the same time, the total projected area of the strands is reduced by one-half, thus increasing the transmission of light and heat. In view of this reduction of projected area, the screen becomes far less conspicuous.

The provision of parallel strands in one direction only to form a screen facilitates cleaning of the same since a cleaning cloth or brush may be easily run along the strands to wipe the same whereas considerable difficulty is encountered normally in attempting to clean cross meshed strands in the same manner.

Also, although horizontally extending parallel strands may be employed to obtain the above

2

advantages of the present invention it has been discovered that by utilizing vertically extending parallel strands the tendency of soot, etc. to collect on such strands is materially reduced. This is due to the fact that the products of combustion tend to settle downward and pile up on any horizontal extending element.

The manner in which the above and other objects of the invention are accomplished will be readily understood on reference to the following specification when read in conjunction with the accompanying drawing wherein:

Fig. 1 is a front perspective view of a fireplace screen embodying my present invention.

Fig. 2 is an enlarged fragmentary rear view of a lower portion of said screen.

Fig. 3 is a transverse sectional view through the screen and is taken substantially along line 3—3 of Fig. 2.

Referring to Fig. 1 in particular, the screen comprises a substantially rectangular frame 10 formed of a relatively strong but resilient metal tubing or the like. A pair of feet 11 in the form of transversely extending metal tubes are integrally attached in spaced relation to each other on the bottom of the lower horizontal extending cross piece 14 of the frame 10. Although the feet 11 may be attached in any suitable manner to the frame they are illustrated as being attached by screws 12 extending through the bottoms of the feet and threadably secured in the frame.

Attached to the lower cross piece 14 is an elongated toothed anchor piece 13 (Figs. 2 and 3). The main portion of the anchor piece 13 is attached, as by welding, to the rear side of the cross piece 14 with the teeth 17 extending downward and out of contact with the surface of the frame. A second anchor piece (not shown), similar to the anchor piece 13, is integrally attached to the rear side of the upper cross piece 15 of the frame 10 but has the teeth thereof projecting upwardly.

A wire 16 is passed in a sinuous manner between the upper and lower toothed anchor pieces and around the various teeth 17, the teeth thus forming spacing means to substantially equally space the various wire strands. The vertical and parallel extending strands of wire thus form a screen which is substantially impervious to the passage of embers and ashes of normal size therethrough.

I have found that wire commercially available as "music wire" is best suited for the purpose since it may be stretched taut between the cross

pieces 14 and 15 without breaking. I have also found that by using wire from 0.008 to 0.012 inch in diameter and forming the teeth 17 so as to space the various strands from $\frac{1}{2}$ to $\frac{1}{4}$ of an inch apart, the resulting screen, although capable of screening embers, etc., is almost invisible when viewing a fire therethrough from a normal distance. The screen thus formed, permits the unrestricted passage of heat therethrough from a fire and allows the fire to be viewed without obstruction.

In threading the wire over the teeth 17 of the anchor pieces 13 on the upper and lower cross pieces 14 and 15, the cross pieces are first sprung inwardly toward each other a certain amount, and while in this condition the wire is threaded over the teeth. The cross pieces 14 and 15 are then allowed to spring back toward their original shape and in doing so stretch the strands of wire or filament 16 taut so that they will normally remain rigid relative to the frame. It is desirable to initially so spring the cross pieces that when later released to tension the wire strands such pieces are still in sprung condition.

In view of the taut condition of the strands 16 and the fact that they are supported only at their ends, any appreciable jarring of the screen will set the strands into vibration and thus tend to throw off any dust, dirt or the like which might possibly cling thereto.

It will be noted that the anchor pieces 13 are located at a mid point on the rear periphery of the lower and upper cross pieces 14 and 15, respectively, and are thus invisible when viewing the screen from the front, as illustrated in Fig. 1.

Having thus described the invention what I desire to secure by United States Letters Patent is:

1. A fireplace screen capable of screening flying embers comprising a frame of resilient material, means for supporting said frame in a vertical position, means at the top and bottom sides of said frame forming teeth, and a wire extending sinuously around said teeth to form parallel strands extending in a vertical direction only, said strands being held under tension and maintaining said frame in sprung condition, said teeth each having a width substantially equal to the spacings between adjacent ones of said teeth whereby to space all of said strands substantially equal amounts.

2. A fireplace screen capable of screening flying embers comprising a substantially rectangular frame of resilient material, means for supporting said frame in a vertical position, an elongated

toothed member extending along the rear of the top side of said frame, a second toothed member extending along the rear of the bottom side of said frame, and a wire extending sinuously around the teeth of said toothed members to form parallel strands, said strands being held under tension and maintaining said frame in a sprung condition, and said teeth having a width substantially equal to the spacings between adjacent ones of said teeth whereby to space all of said strands substantially equal amounts.

3. A fireplace screen capable of screening flying embers comprising a tubular frame of resilient material, means for supporting said frame in a vertical direction, an elongated toothed member integral with the rear of the top side of said frame and having the teeth thereof extending upwardly and away from the surface of said frame, a second elongated toothed member integral with the rear of the bottom side of said frame and having the teeth thereof extending downwardly and away from the surface of said frame, and a wire extending sinuously around the teeth of said members to form parallel strands, said strands being held under tension and maintaining said frame in a sprung condition, and said teeth having a width substantially equal to the spacings between adjacent ones of said teeth whereby to space all of said strands substantially equal amounts.

ROBERT E. BOYDEN.
